COMBINATION CRANE AND PILE DRIVER

Ernest W. Taylor, Jr., and Peter Nielsen, Bay City, Mich., assignors, by mesne assignments, to Industrial Brown-hoist Corporation, Bay City, Mich., a corporation of Delaware

Application May 21, 1953, Serial No. 356,504

12 Claims. (Cl. 61—74)

This invention relates to combination crane and pile drivers and more particularly to means for supporting the pile driver leader in a manner which will automatically fold it to horizontal position upon the lowering of the crane boom.

One of the prime objects of our invention is to design a combination crane and pile driver in which the leader is secured to and supported by the boom of the crane and in a manner which will permit it to be folded horizontally so that the boom with the leader underslung therebeneath will readily clear trestles, bridges, overpasses and the like, as it is transported from one location to another.

Another object of the invention is to design a combination boom and pile driver in which the leader is automatically swung down for transportation and then restored to upright operative position when the boom is adjusted to predetermined positions.

A further object of the invention is to design a combination crane and pile driver in which the leader swings horizontally and moves outwardly relative to the boom when the boom is swung down, so that the entire leader is disposed forwardly of the crane platform and can be separately supported if desired on a companion flat car ahead of the crane.

With the above and other objects in view, the present invention consists in the combination and arrangement of parts, hereinafter more fully described, illustrated in the accompanying drawings, and more particularly pointed out in the appended claims, it being understood that changes may be made in the form, size, proportion, and minor details of construction, without departing from the spirit, or sacrificing any of the advantages of the invention.

In the drawings:

Fig. 1 is a side elevational view of the combination crane and pile driver, the broken lines indicating a flat car and the boom and leader swung down to near horizontal position.

Fig. 2 is a front elevational view thereof, the broken lines indicating various adjusted battering positions of the leader.

Fig. 3 is an enlarged, sectional plan view through the leader taken on the line 3—3 of Fig. 1.

Fig. 4 is an enlarged, sectional, elevational view taken on the line 4—4 of Fig. 2.

Referring now more particularly to the accompanying drawings in which we have shown the preferred embodiment of our invention, the pile driver is shown associated with a suitable carrier or vehicle which in the instant case comprises a locomotive crane carriage 10 upon which is provided a turntable 11 of the locomotive crane type. Revolvably mounted on the turntable 11 is an A-frame 12 and the operator's cab C in which is mounted the necessary mechanical equipment for driving and controlling the device.

A boom 13 is pivotally connected to the front end of the cab structure C by means of a pin 14 and furnishes support for the conventional hammer-accommodating

2

leader 15 in a manner to be presently described, the leader being preferably formed of standard sections with parallel guides 16 provided as usual.

The boom 13 is held in desired position by means of a cable 17, one end of which is anchored to the head of the boom at 18; thence the cable is trained over guide sheaves 19 and 20, and thence leading to and being wound on the hoist drum D provided in the cab of the crane.

Pivots connected to the head of the boom at 22 is a leader hanger unit U, said unit comprising a pair of hangers 23 with a horizontally disposed stop block B spanning said hangers in a position to bear against the adjacent face of the leader to space it from the head of the boom, the lower end of the unit being universally connected by a pair of pins 24, 24" to the horizontally disposed channel brace 25 as shown, thus supporting the leader in vertical position, the stop block B limiting inward swinging movement thereof so as to prevent parallel disposition of the unit U and the leader 15 and thereby permit swinging movement of the unit U to be imparted through the leader even when the leader is in pile driving position.

A strut member M serves to stabilize the lower end section of the leader, one end of the strut being pivotally connected by a pin 26 to a bracket 27 provided preferably on the boom 13, and a screw slide S is secured to the outer end of said strut, said slide being pivotally secured to the slotted leader side channels 28 by means of bolts 29.

A threaded screw 30 is provided in the slide S, and by application of a wrench (not shown), to the ends of the screw 30, the slide can be transversely adjusted as indicated in broken lines in Fig. 2 of the drawings. A stud (not shown) may be mounted in the screw slide channel 31 to secure the slide in its adjusted position.

A strut cable 32 is anchored to the strut at the point 33, thence leading over a sheave 34 provided on the boom and thence being connected to a turn buckle 35 which is attached to the shaft 36 which spans the A-frame, this cable permitting temporary folding of the leader and holding it in folded position when the boom and leader are swung down.

A hammer H, shown in broken lines in Fig. 1, is slidably mounted in the leader 15 between the guide rails 16, and a hammer line 37 is connected to said hammer, thence being trained over a first sheave 38 and a second sheave 39, both of which are journaled between the top brackets 40—40. Thence the line leads downwardly alongside a guide pulley 37' on the boom, and is wound on one of a pair of drums W provided in the crane cab, said drums being driven from the power plant of the crane (not shown) as usual. Similar guide sheaves 41 and 42 are also journaled between the top brackets 40—40 and a pile line 43 is trained over said sheaves and over a second sheave 39 mounted adjacent to the first sheave 39. One end of the pile line 43 is anchored to the leader and the other end is fastened to the second winding drum W.

When it is desired to fold the leader for travel, the hammer H is first lowered to its lowermost position as indicated at H² in Fig. 1, and the boom then may be lowered whereupon relative pivotal movement of the elements U, 15, and M will be effected via the cable 32 to fold the assembly and permit passage under desired clearances.

To place the folded leader assembly on a flat car F, (shown in broken lines in Fig. 1), it is merely necessary to remove the hanger pin 22 and the end of the boom, and the pin 26 at the boom end of the strut.

From the foregoing description, it will be apparent that we have perfected a very simple, practical and eco-

nomical means for folding the crane boom and leader to permit passage under bridges, trestles and other overhead obstacles.

What we claim is:

1. In a mobile crane construction including a mobile platform, a turntable member on said platform, a boom member mounted on said turntable member for swinging movements between raised and lowered positions, and means connected to said boom member for effecting movements of the latter from and to said positions, the combination of a pile driver assembly foldable with said boom member, said assembly comprising a hanger element; means swingably connecting said hanger element to said boom member for swinging movement relative to the latter in an arc; a rigid strut element; means swingably connecting said strut element to one of said members at a point spaced from said hanger element for swinging movement relative to said one of said members in an arc; a leader; pivotal means respectively connecting each of said elements to said leader at spaced points for swinging movements of each of said elements relative to said leader, swinging movement of one of said elements being transmitted via the leader to the other of said elements; means connected at least to one of said elements for effecting swinging movements of said elements; and means interposed between said hanger element and said leader for reaction with both to prevent parallel disposition of said hanger element and said leader when said leader is in a pile driving position.

2. In a mobile crane construction including a mobile platform, a turntable member on said platform, a boom member having one of its ends mounted on said turntable member for swinging movements between raised and lowered positions, and means connected to said boom member for effecting movements of the latter from and to said positions, the combination of a pile driver assembly foldable with said boom member, said assembly comprising a hanger element; means swingably connecting said hanger element to said boom member adjacent to the other end of the latter for swinging movement of said hanger element relative to said boom member in an arc; a rigid strut element; means swingably connecting said strut element to one of said members at a point spaced from said hanger element for swinging movement of said strut element relative to said one of said members in an arc; a leader; means swingably connecting said hanger element to said leader adjacent to one end of the latter; means swingably connecting said strut element to said leader adjacent to the other end thereof, the arrangement being such that swinging movement of one of said elements is transmitted via the leader to the other of said elements to effect movements of said leader towards and away from said boom member; and means connected at least to one of said elements for effecting swinging movement of said elements.

3. The combination set forth in claim 2 wherein said hanger element is shorter in length than said strut element.

4. The combination set forth in claim 2 wherein said strut element is swingably connected to said boom member.

5. The combination set forth in claim 2 wherein the means connecting said hanger element to said leader includes a pair of pivot pins arranged at right angles one to another so as to permit universal movement of said leader relative to said boom member.

6. The combination set forth in claim 2 wherein the means for effecting swinging movements of said elements comprises a cable having one of its ends fixed to said strut element and having an intermediate portion passing over a sheave mounted on said boom member, the other end of said cable being fixed on said turntable member.

7. In a mobile crane construction including a mobile platform, a turntable member on said platform, a boom

member mounted on said turntable member for swinging movements between raised and lowered positions, and means connected to said boom member for effecting movements of the latter from and to said positions, the combination of a pile driver assembly foldable with said boom member, said assembly comprising a hanger element; means swingably connecting said hanger element to said boom member for swinging movement relative to the latter in an arc; a rigid strut element; means swingably connecting said strut element to one of said members at a point spaced from said hanger element for swinging movement relative to said one of said members in an arc; a leader; pivotal means respectively connecting each of said elements to said leader at spaced points for swinging movements of each of said elements relative to said leader, swinging movement of one of said elements being transmitted via the leader to the other of said elements; means interconnecting at least one of said elements with said boom member and said turntable member for effecting swinging movements of said elements and means carried by said hanger element for engagement with said leader to prevent parallel disposition of said leader and said hanger element when said leader is in a pile driving position.

8. In a mobile crane construction including a mobile platform, a turntable member on said platform, a boom member having one of its ends mounted on said turntable member for swinging movements between raised and lowered positions, and means connected to said boom member for effecting movements of the latter from and to said positions, the combination of a pile driver assembly foldable with said boom member, said assembly comprising a hanger element; means swingably connecting one end of said hanger element to the other end of said boom member for swinging movements of said hanger element relative to said boom member in an arc; a strut element; means swingably connecting one end of said strut element to one of said members at a point spaced from said hanger element for swinging movements of said strut element relative to said one of said members in an arc; a leader; means swingably connecting the other end of said hanger element to said leader intermediate the ends of the latter; means swingably connecting the other end of said strut element to said leader at a point spaced from the connection of said hanger element to said leader, the arrangement being such that swinging movements of one of said elements is transmitted via the leader to the other of said elements to effect movements of said leader towards and away from said boom member; and means connected at least to one of said elements for effecting swinging movement of said elements and said leader.

9. The combination set forth in claim 8 including means mounted on said hanger element for engagement with said leader to prevent parallel disposition of said leader and said hanger element when said leader is in a pile driving position.

10. In a mobile crane construction including a mobile platform member, a boom member supported by said first member for swinging movements in a vertical plane between raised and lowered positions, means connected to said boom member for effecting movements of the latter from and to said positions, the combination of a pile driver assembly foldable with said boom member, said assembly comprising a hanger element, means swingably connecting said hanger element to said boom member for swinging movement relative to the boom member in a plane extending in the same general direction as the plane of vertical movement of the boom member, a rigid strut element, means swingably connecting said strut element to one of said members at a point spaced from said hanger element for swinging movements relative to said one of said members in a plane extending in the same general direction as the plane of vertical movement of the boom member, a leader, pivotal means respectively connecting

each of said elements to said leader at spaced points for swinging movements of each relative to said leader in said planes extending in the same general direction as the said plane of movement of the boom member, swinging movement of one of said elements being transmitted via the leader to the other of said elements, means connecting at least one of said elements with one of said boom member and platform member for effecting said swinging movements of said elements relative to said boom member and platform member, and means carried by said hanger element for engagement with said leader to prevent parallel disposition of said leader and said hanger element when said leader is in a pile driving position.

11. In a mobile crane construction including a mobile platform member and a boom member pivotally supported by said first member for swinging movements between raised and lowered positions, the combination of a pile driver assembly foldable with said boom member, said assembly comprising; a hanger element pivotally connected to the boom member, a strut element, means pivotally connecting said strut element to one of said members at a point spaced below the connection of said hanger element for swinging movement relative to said one of said members, a leader, pivotal means respectively connecting each of said elements to said leader at spaced points for swinging movements of each relative to said leader, means interconnecting at least one of said elements and leader with one of said boom member and platform member for effecting folding movement of said leader and strut element in toward said boom member, and means carried by said hanger element for engagement with said leader to prevent parallel disposition of said leader and said hanger element when said leader is in a pile driving position.

12. In a mobile crane construction including a mobile platform, a turntable member on said platform, a boom member having one of its ends mounted on said turntable for swinging movements between raised and lowered positions, and means connected to said boom member for effecting movements of the latter from and to said posi-

5 tions, the combination of a pile driver assembly foldable with said boom member, said assembly comprising a hanger element; means swingably connecting said hanger element to said boom member adjacent to the other end of the latter for swinging movement of said hanger element relative to said boom member in an arc; a rigid strut element; means swingably connecting said strut element to one of said members at a point spaced from said hanger element for swinging movement of said strut element relative to said one of said members in an arc; a leader element; means swingably connecting said hanger element to said leader element adjacent to one end of the latter; means swingably connecting said strut element to said leader element adjacent to the other end of the latter, the arrangement of said boom member and said elements being such that swinging movement of one of said hanger and strut elements is transmitted via the leader element to the other of said hanger and strut elements to effect movements of said leader element towards and away from said boom member; and means interconnecting one of said boom and turntable members and one of said elements for effecting swinging movement of said hanger and strut elements and movement of said leader element towards and away from said boom member.
